(57) **CLAIM**

The ornamental design for a display screen or portion thereof with icon, as shown and described.

DESCRIPTION

FIG. 1 is a first embodiment of a front view of a display screen or portion thereof with icon showing our new design; and, FIG. 2 is a second embodiment thereof.

The broken lines illustrating portions of the display screen or portion thereof with icon are for environmental purposes only and form no part of the claimed design.

1 Claim, 2 Drawing Sheets

FIG. 1

FIG. 2
